UNITED STATES PATENT OFFICE.

AUGUST LOEFFLER, OF TOMPKINSVILLE, NEW YORK.

INSTANTANEOUS SHUTTER FOR PHOTOGRAPHIC LENSES.

SPECIFICATION forming part of Letters Patent No. 313,677, dated March 10, 1885.

Application filed December 2, 1884. (No model.)

To all whom it may concern:

Be it known that I, AUGUST LOEFFLER, of Tompkinsville, in the county of Richmond and State of New York, have invented a new and useful Improvement in Instantaneous Shutters for Photograph-Lenses, of which the following is a full, clear, and exact description.

Reference is to be had to the accompanying drawings, forming a part of this specification, in which similar letters of reference indicate corresponding parts in all the figures.

Figure 1 is a front elevation of one of my improved shutters, part being broken away. Fig. 2 is a sectional side elevation of the same, taken through the line $x-x$, Fig. 1. Fig. 3 is a sectional plan view of the same, taken through the line $y-y$, Fig. 1. Fig. 4 is a side elevation of the upper and middle part of the same.

The object of this invention is to promote convenience in instantaneous photographing, and provide a mechanism simple in construction and reliable in operation for instantly uncovering and covering the lenses, so as to obtain an instantaneous exposure.

The invention relates to an instantaneous shutter for photograph-lenses, constructed with a plate, having opening to receive the lens-tube, a spring-roller, and a plain roller connected with the said plate and provided with a connecting-cloth having central opening, and a handle, ratchet-wheel, and spring-lever pawl, whereby the said rollers can be readily turned and released. The handle is provided with a pin to engage with a latch pivoted to the plate, and limited in its movement by a stop-pin, whereby the said handle will be automatically caught and held against the draft of the spring-roller. The apertured plate is provided with keepers to receive the edge of a plate, having a larger or smaller opening than the main plate and kept in place by a clamping-screw, as will be hereinafter fully described, and then claimed.

A represents the box, and B the lens-tube, of a camera constructed in the ordinary manner.

C is a board or plate, through which is formed a circular aperture to receive and fit upon the outer end of the lens-tube B.

In the drawings the lens-tube B is represented as being smaller than the aperture in the plate C. In this case a board or plate, D, having an aperture of the proper size to receive the end of the lens-tube B, is placed against the rear side of the plate C, and secured at one edge by being passed beneath hook-keepers E, attached to the edge of the plate C, and secured to the other edge by a clamping-screw, F, passing through the said plate D and screwing into the plate C, or into a nut secured to the said plate C.

Several plates, D, with different-sized apertures, are designed to be provided with the shutter, so that the said shutter can be applied to different sizes of lens-tubes.

To the side edges of the plate C are attached bars G, the ends of which project at the upper and lower corners of the said plate, and are perforated to receive the journals of the rollers H I. The lower roller, H, is a spring-roller, and the upper roller, I, is a plain roller.

J is a strip of black cloth or other suitable flexible material, of a width a little less than the breadth of the plate C and of a length about equal to three times the length of the said plate C. The ends of the flexible material J are wound upon and attached to the rollers H I, and in the center of the said strip is formed a square aperture, a little less in size than the plate C.

To the forward side of the side edges of the plate C are attached bars or plates K, the under sides of the inner edges of which are rabbed to receive the side edges of the flexible material, so that the said plates K will serve as guides to keep the said flexible material close to the plate C as it is being wound from one to the other of the rollers H I.

To one of the journals of the upper or plain roller, I, is attached a crank, L, or other suitable handle for turning the roller I to wind the flexible material J upon it, the unwinding of the said material from the spring-roller H coiling up the spring of the said roller H and putting it under tension.

To the inner side of the handle L is attached a pin, M, which, as the said handle revolves, strikes, raises, and passes a catch, N, pivoted to the edge bar G, so as to hold the said han-

idle from turning back, should it be accidentally released, and to hold it in any position into which it may be turned. The catch N is kept from dropping down too low by a stoppin, O, attached to the said bar. The handle L is slotted, and in the space thus formed is placed a lever-pawl, P, the forward end of which engages with a ratchet-wheel, Q, rigidly attached to the journal of the upper roller, I. The outer end of the lever-pawl P is held up, holding its engaging end in gear with the said ratchet-wheel Q by a spiral or other spring, R, interposed between and secured to said handle and pawl.

15 In using the improvement the plate C or D is placed upon the lens-tube B, and the upper roller, I, is turned by turning the handle L until about a third of the cloth J is wound upon the said upper roller, I, bringing the 20 opening in the said cloth opposite the opening in the plate C, as illustrated in Figs. 1 and 2. The lens is then focused. The roller I is turned to wind up another third of the cloth J and bring the lower part of the said cloth 25 over the opening in the plate C. The sensitive plate is then inserted, and at the proper time the pawl P is operated to raise its engaging end away from the ratchet-wheel Q, when the spring-roller H at once winds the 30 cloth J upon the said spring-roller H and the sensitive plate is exposed while the opening in the cloth J is passing the opening in the plate C.

The time required for the opening in the 35 cloth J to pass the opening in the plate C can be lengthened or shortened by giving more or less tension to the spring of the roller H.

Having thus fully described my invention, I claim as new and desire to secure by Letters 40 Patent—

1. In an instantaneous shutter for photograph-lenses, the combination, with the plate C, having opening to receive the lens-tube, of the spring-roller H, the plain roller I, and the flexible material J, attached to the said 45 rollers, and a mechanism for revolving and releasing the rollers, substantially as herein shown and described.

2. In an instantaneous shutter for photograph-lenses, the combination, with the plate 50 C, having aperture, the spring-roller H, the plain roller I, and the cloth J, having central aperture, of the handle L, the ratchet-wheel Q, and the spring lever-pawl P R, substantially as herein shown and described, whereby 55 the said rollers can be readily turned and released, as set forth.

3. In an instantaneous shutter for photograph-lenses, the combination, with the plate C, having aperture, the spring-roller H, the 60 plain roller I, the cloth J, having opening, and the handle, ratchet-wheel, and spring lever-pawl L Q P R, of the pin M, the pivoted latch N, and the stop-pin O, substantially as herein shown and described, whereby the said handle 65 will be automatically caught and held against the draft of the spring-roller, as set forth.

4. In an instantaneous shutter for photographic lenses, the combination, with the plate C, having aperture, and provided with keepers E, of the plate D, having aperture, and the clamping-screw F, substantially as herein shown and described, whereby the shutter can be readily applied to lens-tubes of different sizes, as set forth.

AUGUST LOEFFLER.
